SPECIFICATION forming part of Design No. 12,502, dated October 4, 1881.

Application filed September 2, 1881. Term of patent 3½ years.

To all whom it may concern:

Be it known that I, WALTER J. GADSBY, a subject of the Queen of Great Britain, residing at Boston, in the county of Suffolk and State of Massachusetts, have invented a certain new and original Design for Carpets, of which the following is a specification.

overlying the figures A and ground centers B, as shown.

I claim—

The design for carpets, substantially as hereinafter described.

In testimony whereof I have signed my name to this specification, in the presence of two subscribing witnesses, this 29th day of August, A. D. 1881.
